(57) **CLAIM**

We claim the ornamental design for a hinge, as shown and described.

DESCRIPTION

FIG. 1 is a perspective view of the claimed design; FIG. 2 is a front view of the embodiment of the claimed design shown in FIG. 1; FIG. 3 is a rear view of the embodiment of the claimed design shown in FIG. 1; FIG. 4 is a top view of the embodiment of the claimed design shown in FIG. 1; FIG. 5 is a bottom view of the embodiment of the claimed design shown in FIG. 1; FIG. 6 is a side view of the embodiment of the claimed design shown in FIG. 1; and, FIG. 7 is another side view of the embodiment of the claimed design shown in FIG. 1. The broken lines depict environmental subject matter and form no part of the claim. The dash-dot lines form boundaries of the claimed design.
